(57) **CLAIM**

The ornamental design for a skin massager, as shown and described.

DESCRIPTION

1. Skin massager

Figure 1.1 is a perspective view of a skin massager showing my new design;

Figure 1.2 is a front view thereof;

Figure 1.3 is a back view thereof;

Figure 1.4 is a left view thereof;

Figure 1.5 is a right view thereof;

Figure 1.6 is a top view shown thereof;

Figure 1.7 is a bottom view shown thereof; and

Figure 1.8 is a bottom perspective view thereof.

The broken lines shown in the figures are for the purpose of illustrating portions of the skin massager, which form no part of the claimed design.

1 Claim, 8 Drawing Sheets
